UNITED STATES PATENT OFFICE.

JAMES HARVEY CARPENTER, OF ULYSSES, NEBRASKA.

WASHING-MACHINE.

SPECIFICATION forming part of Letters Patent No. 444,813, dated January 20, 1891.

Application filed August 8, 1890. Serial No. 361,415. (No model.)

To all whom it may concern:

Be it known that I, JAMES HARVEY CARPENTER, a citizen of the United States, and a resident of Ulysses, county of Butler, and State 5 of Nebraska, have invented certain new and useful Improvements in Washing-Machines, of which the following is a specification, the principle of the invention being herein explained and the best mode in which I have 10 contemplated applying that principle so as to distinguish it from other inventions.

My invention has for its object to provide improved means for distributing the suds through the clothes and for circulating said 15 suds.

Referring to the drawings, Figure 1 represents a vertical section of my improved washing-machine; Fig. 2, a perspective view of the machine; and Fig. 3, a perspective detail view 20 of the bottom of the suds-box, the distributing-cone and duct, and the cylinder.

In the drawings, the letter A indicates the suds-box, within which a cylinder C is formed against one side of the box. Said cylinder 25 has a common upwardly-swinging check-valve c³ at its lower end for the admission of suds into it. A cone a' is arranged upon the bottom a⁴ of the suds-box and has perforations a³, through which it communicates with the same. Said cone communicates with the pump-cylinder C through a downwardly-inclined flue a², which communicates with an upwardly-flaring flue a⁶, opening into the lower end of the pump-cylinder. A contracted 30 throat a⁵ is thus formed between the rose or conical spraying or distributing chamber a' and the flue a⁶, which throat will cause the suds to enter said chamber with a rush and to thus be easily distributed when they are 35 forced out of the pump-cylinder C. A piston b² fits and slides in the pump-cylinder, and may be reciprocated within the same by means of a piston-rod b. The upper end of said piston-rod is pivotally connected to a lever 40 B, which is fulcrumed at one end by a link b³ upon an arm or bracket a, projecting from the upper edge of the suds-box. A widely-flaring pounder B' is supported in the suds-box from said lever, having a series of 45 perforations b⁵ in the upper end of its handle 50

b⁴, by means of which it is pivoted upon a pin or bolt upon the lever.

In operation the clothes to be washed are placed in the suds-box, upon the conical rose or distributing-chamber and beneath the 55 pounder. Water and soap, soapsuds, or other washing-liquid is filled in the suds-box, and the lever is then rocked to vertically reciprocate the pump-piston and pounder. This will cause the suds to be circulated in the 60 suds-box and pump, and the suds will be forced up and distributed through the clothes at the same time they are pressed down by the pounder, which combined action of the pump and pounder will cause a thorough working and cleansing of the clothes. The conical form of the perforated rose or distributing-chamber will insure a thorough distribution 65 of the suds, and the corresponding shape of the pounder will insure even pressure upon 70 all the clothes by the same.

The foregoing description and accompanying drawings set forth in detail mechanism embodying my invention. Changes may be made therein provided the principles of construction respectively recited in the following claims are employed.

I therefore particularly point out and distinctly claim as my invention—

1. In a washing-machine, the combination 80 of a suds-box, a pump having inlet and discharge in the bottom of said suds-box, and a pounder in said suds-box and connected to reciprocate with and in the same direction as the piston in said pump, substantially as set 85 forth.

2. In a washing-machine, the combination 90 of a suds-box, a pump, a conical perforated chamber in the bottom of said suds-box and communicating with said pump, and a pounder in said suds-box connected to be reciprocated with and in the same direction as the piston in said pump, substantially as set forth.

3. In a washing-machine, the combination 95 of a suds-box, a pump-cylinder in the same, a conical perforated chamber in the bottom of said suds-box, having a downwardly-inclined flue in one side, an upwardly-flaring flue communicating with said inclined flue 100

and with said pumping-cylinder, a pounder having a flare corresponding to said conical chamber, a pump-piston, and a lever pivoted upon the edge of the suds-box and having
5 said pounder and piston pivotally connected to it, substantially as set forth.

In testimony that I claim the foregoing to

be my invention I have hereunto set my hand this 4th day of August, A. D. 1890.

JAMES HARVEY CARPENTER.
